UNITED STATES PATENT OFFICE.

CHARLES WILLIAM KROMENAKER, OF CHICAGO, ILLINOIS.

BOOK-MARKER.

SPECIFICATION forming part of Letters Patent No. 664,417, dated December 25, 1900.

Application filed July 20, 1900. Serial No. 24,345. (No model.)

To all whom it may concern:

Be it known that I, CHARLES WILLIAM KROMENAKER, a citizen of the United States, residing at Chicago, in the county of Cook and State of Illinois, have invented certain new and useful Improvements in Book-Markers; and I do hereby declare the following to be a full, clear, and exact description of the invention, such as will enable others skilled in the art to which it appertains to make and use the same.

My invention relates to book-markers, and more particularly to that variety thereof designed for the use of stenographers in connection with the books or writing-tablets commonly used for taking stenographic notes; and my invention consists of certain novel features of combination and construction of parts, the preferred form or embodiment whereof will be set forth in the following specification and illustrated in the accompanying drawings.

The object of my invention is to provide a simple cheap, through reliably efficient, device of the character specified which may be readily disposed in its operative position upon or in connection with a tablet, whereby the pages filled with stenographic notes or other data may be readily kept separated from notes or data previously transcribed, while the last page used may also be readily ascertained.

Other objects and advantages will be made fully apparent from the following specification.

In the accompanying drawings, Figure 1 is a top plan view of my attachment complete. Fig. 2 is an end view thereof, both of said views showing the device in a folded position ready for use. Fig. 3 is an end view showing the parts disposed substantially in that position which they will occupy when in use. Fig. 4 is a detail view showing two of the parts of my device separated from each other. Fig. 5 is another view of the same parts shown in Fig. 4. Fig. 6 shows my invention as applied to use upon an ordinary stenographic notebook. Fig. 7 is a detail plan view showing a cardboard or other form of back or body portion to which my book-marker is secured.

In order to conveniently refer to the several features of my invention and their co-operating accessories, numerals will be em-

ployed, of which 1 indicates a portion of the framework of my book-marker, which may be cheaply formed of wire or other suitable material and are of any desired length and are designed to reach across the end of the note-book, the same being preferably disposed immediately beneath the cover of the book. I prefer to dispose one of the sections 1 upon each side of the stitching of the book, which may be readily done by spreading the parts 1 sufficiently to enter the pages of the book, the cover portion being then wrapped over said sections. By this disposition of the sections 1 they will be entirely out of sight, excepting the end portions thereof. The ends of the sections 1 are properly bent to provide the eyes 2 and are adapted to receive the eyes or link-sections 3 and 4, formed, respectively, upon the partitioning-sections 5 and 6, which latter are disposed parallel with each other, though preferably separated, in order to better perform their office of separating the leaves of the book to which my invention is applied. The sections 5 and 6 are preferably formed of wire properly bent at their extreme ends to form the link-sections 3 and 4, respectively. In Fig. 5 it will be observed that the eyes 2 are engaged by both the eyes or links 3 and 4, thereby holding the sections 1 in a position substantially parallel to each other, ready to be swung apart sufficiently to receive the leaf or body section of the book, it being understood, as above set forth, that the cover thereof must wrap over or extend upon the outer side of the sections 1, thus preventing the book from dropping entirely through between said sections.

In Fig. 6 it will be seen that the section 5 is disposed in advance of a number of pages of the book, while the section 6 is disposed still farther in advance, there being a number of pages between the sections 5 and 6 which we will assume have just been filled with stenographic notes, while the pages in advance of the section 5 are those pages which have just been transcribed upon the typewriter. The pages in advance of the section 6 are blank pages, and as each of these pages is filled with data it can be tucked behind the section 6, and thus disposed with the pages that have been filled, though not yet transcribed, it being understood that the pages

just written by the stenographer in shorthand and not yet transcribed by the type-writer are always between the sections 5 and 6, while those pages which have been written upon the 5 type-writer are behind the section 5.

In Fig. 7 I have shown a writing-tablet or base designed to support the flexible book usually employed in connection with my attachment, and said writing-tablet or base will 10 for convenience be designated by the numeral 7. The base 7 may be made of heavy cardboard or other preferred material and is preferably provided at each corner with an eyelet 8, by means of which it can be oper- 15 atively connected to my improved book-marker by means of a split ring 9, as clearly shown in Fig. 6. By means of the base-section 7 a desirable support is provided for the writer when no table, desk, or the like is conven- 20 iently at hand.

It will be understood that my improved book-marker may be constructed of any material deemed suitable for the purpose and the parts thereof quickly assembled in their

respective operative positions, and while I 25 have described the preferred construction of the several parts it will be understood that I desire to comprehend in this application all such equivalents and substitutes as may be considered to fall fairly within the scope of 30 my invention.

What I claim as new, and desire to secure by Letters Patent, is—

The herein-described book-marker comprising the sections 5 and 6 provided with the eyelets 3 and 4 respectively; a pair of anchoring-sections 1 connected to said eyelets; a base-section 7 and means to connect said section to the eyelets 2 formed upon the ends of the section 1, all substantially as specified and 40 for the purpose set forth.

In testimony whereof I affix my signature in presence of two witnesses.

CHARLES WILLIAM KROMENAKER.
